HENRY L. DOHERTY, OF NEW YORK, N. Y.

APPARATUS FOR BURNING CARBONACEOUS MATERIAL.

1,192,998.

Specification of Letters Patent.

Patented Aug. 1, 1916.

Application filed January 17, 1911. Serial No. 603,086.

To all whom it may concern:

Be it known that I, HENRY L. DOHERTY, a citizen of the United States, and a resident of New York city, in the county of New York and State of New York, have invented certain new and useful Improvements in Apparatus for Burning Carbonaceous Material, of which the following is a specification.

10 This invention relates to traveling grates, and, in particular, to a form of said apparatus specially adapted for carrying a comparatively deep bed of fuel, so that the fuel may be burned on the grate by partial combustion to produce combustible gas. The apparatus is, however, equally well adapted for use with so-called direct-fired furnaces, in which the fuel is subjected to complete combustion on the grate.

20 The object of this invention is to provide a means for burning carbonaceous material supported upon a moving grate in such a way that the quantity of air passed through any part of the fuel bed will approximately correspond to the quantity of unconsumed carbon in the said part of the bed.

Whenever a chain-grate or the like is fed with fresh fuel at one end of its inclosing chamber and discharges the resulting burned material at the opposite end of the chamber, the quantity of unconsumed fuel therein will, obviously, decrease from the feed to the discharge end where the proportion of carbon in the mass on the grate will be comparatively small, usually from 6 to 20%. When the air supplied for the combustion has unrestricted access to all parts of the grate, there is a tendency for the greater part of the air to pass through the thinnest part of the fuel bed near the ash-discharge end of the furnace chamber. This results in a greater or less excess of free air passing through the fuel bed and appearing in the combustion gases, thus reducing their temperature, or else burning a corresponding quantity of the producer gas, when the furnace is being run as a gas producer.

My invention is designed to overcome this defect, by regulating the flow of air to the fuel bed approximately according to the quantity of combustible therein.

In the accompanying drawings, I have shown my invention applied to the firing of the gas producer of a gas-fired furnace. It

is evident, however, that it may be applied in connection with any direct or gas-fired furnace.

Figure 1 is a vertical longitudinal section taken through the center of the gas producer showing the grate in longitudinal section. Fig. 2 is a part elevation detail of the chain or traveling grate and one of the sprocket wheels carrying the same, showing two of the links or grate-bars in section. Fig. 3 is a plan view of Fig. 2, but showing the left end link or bar in section, said section being taken through the uppermost row of air passages of the grate bar. Fig. 4 is a view showing the mechanism used for driving the sprocket wheel which, in turn, moves the traveling grate at the required speed.

Briefly, my invention comprises a gas-producing chamber, a continuous chain-grate, working about the two sprocket wheels 7 and 7' and receiving its motion therefrom, an inclined baffle placed within the space enclosed by the traveling grate, and various other features appurtenant to the above.

The drawings show my invention applied to a furnace in which coal, 1, and clinkers, 2, are fed into a hopper, 3, which has a partition, 4, so as to keep the clinkers and coal from intermingling while in the hopper 3. The clinker and coal compartments of the hopper 3 have their respective covers, 5 and 6. As the sprocket wheel, 7, is made to slowly rotate in the direction of the arrow by some suitable driving gear it causes the upper part of the chain grate, 8, to assume a motion toward the opposite end of the producer, from that where the fuel is fed, the rate of motion being regulated to correspond with, and depending upon, the rate of gasification of the fuel 1 upon the grate 8, and being so adjusted that by the time the fuel fed in at the front end of the producer has been burned to the desired degree it will be discharged from the grate 8 to the grate 9 at the rear of the producer 10. On the grate 9, the mass of clinker and any unburned fuel discharged from grate 8, is subjected to the action of a draft-current of air to burn out residual carbon.

The clinker being fed into the producer under the fuel, will form a layer of non-combustible material upon the grate 8 and thus protect it from excessive heat during

gasification. The gas formed in the producer 10, in the furnace shown, is led to the combustion chamber 12 through the gas off-take 11 which leads into the combustion chamber tangentially and diametrically opposite the secondary air supply inlet 13, which accounts for its connection to the combustion chamber 12 not being shown in Fig. 1. As the gas enters at the lower part of the combustion chamber 12 it is mixed with air entering through the flue 13 on the opposite side of the chamber. The height of the combustion chamber should be such as to allow several convolutions of the gaseous stream, thus obtaining a thorough mixture and complete combustion before leaving the combustion chamber through the flue 14.

The combustion chamber 12 is of circular cross-section. The air and gas are entered tangentially at opposite sides, thus forming a helical flame. By this device I have found that I can secure a very complete and rapid combustion of the producer gas with the minimum supply of air, thus insuring a very high flame temperature. This form of combustion chamber and method of combustion I do not claim herein as I have claimed it in my application Ser. No. 356,414, filed Feb. 8, 1907.

14 is the combustion gas off-take which conducts the hot gases to the place of use, for example, a steam generating chamber.

The flue 38 and damper 39 allow the withdrawal of a portion of the combustion gases from the chamber 16, to be injected under the grate in mixture with the primary air if so desired so as to regulate the temperature of combustion in the producer.

9 is a stationary grate to receive the ashes resulting from the combustion of the fuel on the grate 8, and 40 is a pipe leading air from the main supply pipe 41 under the grate 9 so as, if desired to burn any fuel which may have escaped combustion while passing through the producer 10.

40', 42' and 43' are valves controlling the flow of air through the respective pipes 40, 42 and 43.

Applying my invention to the apparatus shown, the method of operation is as follows: Assuming that the producer has been brought up to proper operating condition, the fuel bed 1 will have a varying thickness or depth along its length due to the progressing state of combustion of the fuel along said length; that is, the fuel bed will be thicker or deeper at the charging point where the fuel just begins to burn and the depth will decrease from this point to the opposite end of the producer, or discharge end, where the bed consists practically of ashes and little or no combustible material and at which point the bed has its least depth. From this state of affairs it is evident that the amount of combustible material upon the

grate, and therefore the amount of air required for its combustion, decreases, along the grate, from the maximum amount at the charging point to the minimum amount at the discharging point. There should therefore be some way of controlling the distribution of the air used in the combustion of the fuel on the grate 8 so that the volume of air passing through the grate and fuel bed, at any point along its length, will be proportional to the amount of combustible material at that point. As stated before, this distribution of air may be obtained by using an inclined baffle, 45, which compels a greater portion of the draft current 80 entering under the fuel bed through the injector 44 to pass through the front or charging point of the producer, where the fuel bed has its greatest thickness and contains the largest amount of unburned combustible material, and causes a gradual decrease in the volume passing through the fuel bed along the length of the grate. Therefore at the point of least depth of fuel bed where there is very little combustible material, the volume of air passing therethrough is a minimum. The grate, 8, and consequently the fuel thereon, has a slow continuous motion in the direction of the arrows, the rate of travel being such as to give ample time for the carbon of the fuel to be for the most part burned out by the time it reaches the discharging end, where the ashes are discharged upon the secondary stationary grate 9. The main air-supply 100 pipe 41 has three branches, one conducting the primary air through the pipe 43 to the injector 44. The second current of air is led to the combustion chamber through the tangential inlet 13 through the pipe 42, and the third current is led through the small pipe 40 under the grate 9 through which it passes and burns any combustible material which has escaped complete combustion in its passage through the producer 10. The 110 gases generated in the producer 10 are led to the combustion chamber 12 where they come in contact with the secondary air and are burned. The resulting combustion gases, as mentioned before, are led to a furnace 115 through the flue 14. A portion of the combustion gases is returned to the producer 10, under the grate 8, by the action of the injector 44, through the flue 38, the volume thus returned being controlled by the damper 39.

It is evident, that if the volume of air for combustion of the fuel in the producer 10 was allowed to be the same along the whole length of the grate, that there would be a large excess of air passing through the rear end of the grate, where there is little combustible material left in the bed, when the proper volume of air was being allowed to pass through the front end of the grate, 120

where the amount of combustible material in the fuel is comparatively large. On the other hand, working with a uniform flow of air along the length of the grate, if only 5 the required amount of air were allowed to pass through the grate to burn the combustible material in the rear of the grate there would result a deficiency in the amount of air being supplied to the front end of the 10 producer, where the fuel bed has a larger proportion of combustible material. Again, doing away with the baffle 45 and allowing a volume of air to pass through the grate to properly burn the fuel in the middle of 15 the grate would have the evil effects that the fuel in the front of the producer would have an insufficient volume of air passing therethrough for proper combustion, and the fuel on the rear part of the grate would have an 20 excess of air passing therethrough. It is therefore evident that, for proper combustion of the fuel along the entire length of the grate, it is essential to proportion the volume of air passing different sections 25 thereof to the amount of combustible material left in the fuel at the said sections. It is also essential that the grate, upon which the traveling fuel bed is supported, be of such design that, although it will allow the 30 air required for the proper combustion of the fuel thereon to pass therethrough, it will prevent the passage of the fuel, and ashes resulting from the combustion of the same. The grate, which I have shown, is 35 of novel construction and admirably adapted to fill the requirements stated above to be essential to the proper operation of the invention.

92 are the linked bars comprising the 40 grate 8. These bars, when assembled to form the grate 8, prevent the fuel or ashes from falling through it to the chamber 46 and, at the same time, permit free passage of the air required for combustion of the 45 fuel. This is preferably accomplished by having bars as shown in Fig. 2, which contain numerous slots, 93, the slots being preferably inclined as shown, so that the air may pass through, while the fuel cannot work 50 itself up through the inclined slots.

The bars have a shorter side fixed at, approximately, right angles to the conveyer chain and a longer side inclined thereto. The bars are, preferably, set with their inclined side in advance of the shorter side. As the bars are preferably slotted on the advance side only, in order that ashes will not work through the bars while the same are passing over the sprockets or drums at the discharge end (as they would were the bars slotted on the rearward side) it is advantageous to have the inclined side in advance in order to take advantage of the greater slot area thereby made available. 65 The advantage in having the one side sub-

stantially perpendicular to the upper flight of the conveyer chain is that the span of the bars is thereby made shorter, thereby permitting the inclusion of a greater number of bars in the train. The inclination of 70 the other side of the bars may be fixed according to the preference of the designer, within certain limits, the aim being to have the inclined side long enough to permit of sufficient slot area for the proper supply of 75 air, while, at the same time, not unduly increasing the span of the bar.

The driving shaft 7" has two sprocket wheels, 7, keyed to it, only one of which is shown in Figs. 2 and 4. Pins, 94, connect, in the arrangement shown, the rear lower side of one grate-bar with the front lower side of the adjacent grate-bar, and they project beyond both ends of the links 92 and through the two heavy links 95 and 95', 85 which latter links when assembled form the sprocket chain which is directly driven by the wheels 7 and thus imparts motion to the grate as a whole. The links 95 with their corresponding links 95' are spaced apart so that the teeth 96 of the wheel 7 may pass between them and engage the cross pins 97, by which means the grate is carried around by the wheel 7 in the direction of the arrow.

The bars 92 project into the recess 98 in the side walls 46 and 46', 46' only being shown, leaving as small a clearance as practicable between them and the walls 46 and 46' on the upper side of the grate. At the ends of each bar 92, the projecting lugs 99, 100 extend over the joints of the links and prevent whatever material may work itself through the clearance from getting in the joints.

The driving shaft 7" extends through the 105 side wall through a heavy bearing 7" and is driven by any suitable reducing gearing. As the forward speed of the fuel on the grate 8 must be very slow in order to allow a sufficient length of time for the gasification of the fuel during its passage through the length of the gas producer 10, the reduced speed ratio of the engine shaft and the shaft 7" must be large. In the drawings, Fig. 4 shows one method for obtaining 110 such speed reduction, in which 100 is a worm on the main driving shaft, 100', driving the large worm gear 101. The worm gear 101 is keyed to the shaft 102, on which is another worm, 103, which, in turn, drives the 115 second worm wheel, 104, which is keyed to the driving shaft 7", driving the wheels 7 as already explained. By increasing the number of teeth on the worm wheels, or by increasing the number of wheels and worms, 120 any reduction of speed desired may be obtained.

105 and 106 are supports for the shafts 102 and 7", respectively.

107 indicates a means for guiding the up- 125

per part of the grate 8 between the sprocket wheels, the projecting pieces 99 which prevent material from getting into the joints of the links slide upon these Z-pieces which are supported in the walls of 10, and the part of the grate supporting the fuel is prevented from sagging.

Having described my invention, what I claim is:

10. A traveling grate comprising a plurality of grate-bars having an inverted trough-shape on the upper run of the grate, the said grate-bars each having one side longer than the other and having a plurality of apertures in the said longer side for the passage of air therethrough, and means for joining the short side of each grate-bar to the long side of an adjacent bar to form an endless train, the junctures between said 20 grate-bars being substantially ash-tight.

2. A traveling grate comprising a plurality of grate-bars of substantially uniform cross-section and having an inverted trough-shape on the upper run of the grate, the 25 said bars each having one side longer than the other and having a plurality of apertures in the said longer side for the passage of air therethrough, said apertures being inclined downward from the interior of said 30 grate-bars, and means for joining the short side of each grate-bar to the long side of an adjacent grate-bar to form an endless train.

3. A traveling grate comprising a plurality of grate-bars of substantially uniform 35 cross-section and of inverted trough shape on the upper arm of the grate, the said grate-bars each having one side longer than the other, the length of the said longer side being approximately equal to the length of the said 40 shorter side divided by the cosine of the angle included between the said sides, the said longer side having a plurality of apertures therein.

4. A traveling grate comprising a plurality of grate-bars of substantially uniform 45 cross-section and having an inverted trough-shape on the upper run of the grate, the said grate-bars each having one side longer than the other, the length of the said longer side 50 being approximately equal to the length of the said shorter side divided by the cosine of the angle included between the said sides and having a plurality of apertures, and means for joining the short side of each 55 grate-bar to the long side of an adjacent grate-bar to form an endless train.

5. A traveling grate comprising a plurality of grate-bars having an inverted trough-shape when on the upper run of the 60 grate, the said grate bars each having one side longer than the other, the length of the said longer side being approximately equal to the length of the said shorter side divided by the cosine of the angle included between 65 the said sides and having a plurality of apertures.

clined apertures for the passage of air therethrough, said apertures leading from the interior of said grate-bars in a direction away from the vertex of said angle, and means for joining the short side of each 70 grate-bar to the long side of an adjacent grate-bar to form an endless train.

6. A traveling grate comprising a plurality of grate-bars having an inverted trough-shape on the upper flight of the 75 grate, the said grate-bars each having one side longer than the other, the length of the said longer side being approximately equal to the length of the said shorter side divided by the cosine of the angle included 80 between the said sides the said longer side having a plurality of inclined apertures for the passage of air therethrough, said apertures leading from the interior of said grate-bars in a direction away from the vertex of said angle, means for joining said 85 grate-bars side to side to form an endless train, said train having an upper and a lower flight, and a baffle located between said flights and adapted to retard the flow of air toward the rear end of the said upper flight of said grate.

7. A traveling grate comprising a plurality of grate-bars of inverted V-shaped 95 cross-section when on the upper run of the grate, one side of said grate-bars having apertures therein for the passage of air therethrough, said grate-bars being directly joined side to side to form an endless train.

8. A traveling grate comprising a plurality of grate-bars of inverted V-shaped cross-section when on the upper run of the 100 grate, one side of each of said grate-bars having apertures therein for the passage of air therethrough, said apertures being so disposed as to prevent material upon said 105 grate from passing therethrough, said grate-bars being directly joined side to side to form an endless train.

9. A traveling grate comprising a plurality of grate-bars of inverted trough-shaped cross-section when on the upper run of the 110 grate, said grate-bars having a plurality of apertures for the passage of air therethrough, said apertures being so disposed as to prevent material upon said 115 grate from passing therethrough, said grate-bars being directly joined side to side to form an endless train in such manner as to form substantially ash-tight junctures between 120 the bars.

10. A traveling grate comprising a plurality of grate-bars of inverted trough-shaped cross-section when on the upper run of the 125 grate, said trough-shaped grate-bars having a plurality of apertures in the sides for the passage of air therethrough, said apertures being inclined downward from the interiors of said grate-bars, and means for directly joining said trough-shaped 130

grate-bars side to side to form an endless train, the junctures between said grate-bars being substantially ash-tight.

11. A traveling grate comprising a plurality of grate-bars having an inverted trough-shape when on the upper run of the grate, the said grate-bars each having one side longer than the other and having a plurality of apertures in the advance side for the passage of air therethrough, and means for joining said grate-bars side to side to form an endless train, the junctures between said grate-bars being substantially ash-tight.

12. A traveling grate comprising in combination a plurality of trough-shaped grate-bars, said grate-bars being in inverted position on the upper run of the grate and having one side set substantially perpendicular to the horizontal when in functional position, said grate-bars having a plurality of apertures, said apertures being arranged to permit free passage of air and to prevent the gravity flow of solid material therethrough, joining means for joining said grate-bars side to side to form an endless train, and means for transmitting motion to said endless train, said means comprising sprocket chains attached to and coöperating with said endless train, and sprocket wheels coöperating with said sprocket chains.

13. A traveling grate comprising in combination, a plurality of trough-shaped grate-bars, said grate-bars being set inverted and with one side substantially perpendicular to the horizontal and the other side inclined when in functional position on the upper run of the grate, the sides of said trough-shaped grate-bars having a plurality of apertures, said apertures being arranged to permit free passage of air but to prevent the gravity-flow of solid material therethrough, joining means for flexibly joining the perpendicular side of one grate-bar to the inclined side of an adjacent grate-bar, whereby said grate-bars are joined side to side to form an endless train, means for imparting motion to said endless train, said means comprising sprocket links spanning the interval between the extremities of the two sides of each grate-bar, the links of adjacent bars being pivotally connected to form an endless sprocket chain, a laterally-projecting lug attached to each end of each of said grate-bars and extending over the pivotal connection of the sprocket link of that grate-bar with the sprocket link of an adjacent grate-bar, sprocket wheels coöperating with said sprocket chain, and means for rotating said sprocket wheels.

14. A traveling grate comprising in combination, a plurality of trough-shaped grate-bars, the said grate-bars being set inverted on the upper run of the grate and of substantially uniform cross-section and having

one side longer than the other, said grate-bars having a plurality of apertures in their sides, said apertures being inclined outwardly and away from the vertices of said trough-shaped grate-bars, whereby free passage is provided for air but the gravity-flow of solid material through said grate-bars is prevented when said grate-bars are in functional position, means for flexibly joining the shorter side of each grate-bar to the longer side of an adjacent grate-bar to join said grate-bars side to side to form an endless train, means for imparting motion to said endless train, said means comprising sprocket links spanning the space between the two sides of each of said grate-bars, the links of adjacent bars being pivotally connected to form an endless sprocket chain, a laterally-projecting lug attached to each end of each of said grate-bars and extending over the pivotal connection of the sprocket link of that grate-bar with the sprocket link of an adjacent grate-bar, sprocket wheels coöperating with said sprocket chains, and means for rotating said sprocket wheels to impart motion to said chains and the attached grate-bars.

15. A traveling grate comprising in combination a plurality of trough-shaped grate-bars, said grate-bars being laid transversely to the direction of travel of said grate and inverted on the upper run of the grate and having one side shorter than the other, the longer side of each of said grate-bars having a plurality of apertures therein, said apertures being inclined outwardly and away from the vertex of said trough-shaped grate-bar, whereby passage is provided for air but the gravity-flow of solid material through said apertures is prevented when said bars are in functional position, means for pivotally joining the shorter side of each grate-bar to the longer side of an adjacent grate-bar to join the said grate-bars side to side to form an endless train, means for imparting motion to said endless train, said means comprising sprocket links spanning the space between the sides of each of said grate-bars, the links of adjacent grate-bars being pivotally connected to form an endless sprocket chain, a laterally-projecting lug attached to each end of each of said grate-bars and extending over the pivotal connection of the sprocket link of that grate-bar with the sprocket link of an adjacent grate-bar, a pair of sprocket wheels suitably mounted on a shaft to coöperate with said sprocket chains at each end of said grate, and a double worm gear for imparting rotation to one of said shafts, whereby motion is imparted to said traveling train.

16. A traveling grate comprising in combination, a plurality of trough-shaped grate-bars of substantially uniform cross-section, the said grate-bars being set inverted on the

upper run of the grate and having one side longer than the other, said grate bars having a plurality of apertures in one side, said apertures being so positioned as to permit 5 the passage of air while preventing the gravity-flow of solid material therethrough, means for joining said grate-bars side to side in pivotal connection to form an endless train, and an inclined baffle for regulating the distribution of air along the length 10 of said grate.

17. A traveling grate comprising in combination, a plurality of trough-shaped grate-bars each of said grate-bars having a relatively short side and a relatively long side and being set inverted on the upper flight of the grate, the length of the said relatively long side being approximately equal to the length of the relatively short side divided 15 by the cosine of the angle included between the sides, one side of each of said grate-bars having a plurality of apertures, means for joining said grate-bars side to side in pivotal connection to form an endless train, and an 20 inclined baffle for diminishing the flow of air along said grate in the direction of travel of the upper flight of said grate.

18. A traveling grate comprising in combination, a plurality of trough-shaped grate-bars, each of said grate-bars having a relatively short side and a relatively long side and being set inverted on the upper flight of the grate, the length of the said relatively long side being approximately equal to the 30 length of the relatively short side divided by the cosine of the angle included between the sides, the longer side of each of said grate-bars having a plurality of apertures, said apertures being inclined outwardly and 35 away from the vertex of said grate-bar, means for joining said grate-bars side to side in pivotal connection to form an endless train, and an inclined baffle interposed between the flights of said endless train to 40 diminish the flow of air toward the discharge end of said grate.

19. A traveling grate comprising in combination, a plurality of trough-shaped grate-bars, the said grate-bars having a relatively 50 short side and a relatively long side and being set inverted on the upper flight of the grate, one side of each of said grate-bars having a plurality of apertures therein, said apertures being inclined outwardly and 55 away from the vertex of said trough-shaped grate-bar, means for joining the short side of each grate-bar to the long side of an adjacent grate-bar to form an endless train, said train having an upper rearwardly moving 60 flight and a lower outwardly moving flight, an inclined baffle interposed between the flights of said grate, said baffle having its rear portion in close juxtaposition to the lower face of the upper flight of said endless train and extending forward and down- 65

ward therefrom, whereby the flow of air along said grate is diminished in a direction toward the rear of said grate.

20. A traveling grate comprising in combination, a plurality of trough-shaped grate-bars, each of said grate-bars having a relatively short side and a relatively long side and being set inverted when on the upper flight of said grate, the length of the said relatively long side being approximately 70 equal to the length of the said relatively short side divided by the cosine of the angle included between the sides, one side of each of said grate-bars having a plurality of apertures, said apertures being inclined outwardly and away from the vertex of said trough-shaped grate-bar, means for joining the said relatively short side of each grate-bar to the said relatively long side of an adjacent bar to form an endless train, said 75 train having an upper rearwardly moving flight and a lower outwardly moving flight, an inclined baffle interposed between the flights of said grate, said baffle having its rear portion in close juxtaposition to the 80 rear portion of the lower face of the said upper flight of said grate and extending forward and downward toward the front end of said grate, whereby the flow of air along said grate is diminished in a direction 85 toward the rear of said grate.

21. A traveling grate comprising in combination, a plurality of trough-shaped grate-bars, the said grate-bars being set inverted when on the upper flight of the grate and 100 having their sides rigidly joined, a plurality of lugs projecting from each of the sides of each of said grate-bars, said lugs being so spaced on the respective sides of the respective grate-bars that the lugs on adjacent sides of adjacent grate-bars will intermesh with each other when said grate-bars are assembled in functional combination, and means for joining said grate-bars side to side to form an endless train. 105

22. A traveling grate comprising in combination, a plurality of grate-bars, said grate-bars having an inverted trough-shape when on the upper run of the grate and having their sides rigidly joined, a plurality of 115 lugs projecting from each side of each of said grate-bars, said lugs being so spaced on the respective sides of the respective grate-bars that the lugs on adjacent sides of adjacent grate-bars will intermesh with each other when said grate-bars are assembled in functional combination, longitudinal perforations in said lugs, the said perforations in the said lugs of each side of said grate-bars being arranged in alinement, the alinement of said perforations of the said lugs of adjacent sides of adjacent grate-bars being so positioned that the two sets of perforations will be in alinement with each other when the said grate-bars are assembled in 120 125 130

- functional combination, and a plurality of bearing pins, one of said pins being inserted through the alined perforations of the lugs of adjacent sides of adjacent grate-bars 5 when said grate-bars are assembled, whereby the said grate-bars are joined side to side to form an endless train.
23. A traveling grate comprising in combination, a plurality of grate-bars having an inverted trough-shape when in the upper end of the grate, a plurality of lugs projecting from each side of each of said grate-bars, said lugs being so spaced on the respective sides of the respective grate-bars that the 10 lugs on adjacent sides of adjacent grate-bars will intermesh with each other when said grate-bars are assembled in functional combination, said lugs being provided with longitudinal perforations and said perforations in the said lugs of each side of said grate-bars being arranged in alinement, the alinement of the said perforations of the said lugs of adjacent sides of adjacent grate-bars being so positioned that the two sets of 15 perforations will be in alinement with each other when the said grate-bars are assembled in functional combination, a plurality of bearing pins, one of said pins being inserted through the alined perforations of the 20 lugs of adjacent sides of adjacent grate-bars when said grate-bars are assembled to join said grate-bars side to side to form an endless train, and a plurality of sprocket links spanning the space between the sides of said 25 grate-bars, said sprocket links being joined together by and pivoted on said bearing pins.
24. A traveling grate comprising in combination, a plurality of trough-shaped grate-bars set inverted when in the upper flight of the grate, a plurality of lugs projecting from each side of each of said grate-bars, said lugs being so spaced on the respective sides of the respective grate-bars that the 30 lugs on the adjacent sides of adjacent grate-bars will intermesh with each other when said grate-bars are assembled in functional combination, said lugs being provided with longitudinal perforations and said perforations in the said lugs of each side of said 35 grate-bars being arranged in alinement, the alinement of the said perforations of the said lugs of adjacent sides of adjacent grate-bars being so positioned that the two sets of perforations will be in alinement with each other when the said grate-bars are assembled in functional combination, a plurality of bearing pins, one of said pins being inserted through the alined perforations of the lugs of adjacent sides of adjacent grate-bars when said 40 grate-bars are assembled to join said grate-bars side to side to form an endless train, said train having an upper flight and a lower flight, a plurality of sprocket links spanning the distance between the sides of said 45 grate-bars, said sprocket links being joined together by and pivoted on said bearing pins, a pair of sprocket wheels suitably mounted on a shaft to coöperate with said sprocket 50 chains at each end of said grate, means for imparting rotation to one of said shafts, and an inclined baffle interposed between the flights of said endless train, said baffle having its rear portion in close juxtaposition to the lower face of said upper flight and extending forward and downward therefrom.
- Signed at New York city, in the county of New York and State of New York, this 16th day of January, A. D. 1911.
